FOREIGN PATENT DOCUMENTS

EM 006613824-0001 * 7/2019

Primary Examiner — Michael A. Pratt*Assistant Examiner* — Wendy L Arminio*(74) Attorney, Agent, or Firm* — Brooks Kushman P.C.(57) **CLAIM**

The ornamental design for a rim lid for cup, as shown and described.

DESCRIPTION

FIG. 1 is a front side perspective view of a rim lid for cup;

FIG. 2 is a rear side perspective view of FIG. 1;

FIG. 3 is a front side view of FIG. 1;

FIG. 4 is a rear side view of FIG. 1;

FIG. 5 is a right side view of FIG. 1, the left side view being a mirror image thereof;

FIG. 6 is a top plan view of FIG. 1; and,

FIG. 7 is a bottom plan view of FIG. 1.

The broken lines depict portions of the rim lid for cup that form no part of the claimed design.

The shading in the Figures represents translucent regions of the rim lid for cup.

1 Claim, 3 Drawing Sheets(56)
